UNITED STATES PATENT OFFICE.

JOSEPH DECELLES, OF WOONSOCKET, RHODE ISLAND.

WRINGING MACHINE.

Application filed November 17, 1922. Serial No. 601,554.

To all whom it may concern:

Be it known that I, JOSEPH DECELLES, a citizen of the United States, residing at Woonsocket, in the county of Providence and State of Rhode Island, have invented new and useful Improvements in Wringing Machines, of which the following is a specification.

My present invention pertains to wringers such as are generally employed in connection with clothes washing machines, and it contemplates the provision of an attachment for such wringers through the medium of which liability of injury to the hands or fingers of a person employing the wringer will be practically eliminated.

The invention further contemplates the provision of an attachment for clothes wringers that may be easily and quickly positioned either on the left or right hand side of the wringer rolls, and one that will feed the clothes to the wringer rolls in an automatic and even manner.

The invention in all of its details will be fully understood from the following description and claims, when the same are read in connection with the drawings, accompanying and forming part of this application, in which:

Figure 1 is a top plan view illustrating my novel feed mechanism as properly positioned on a clothes wringer.

Figure 2 is an end elevation of the wringer head having my novel safety attachment secured thereto.

Figure 3 is a sectional view taken through the longitudinal or transverse center of Figure 1.

Similar numerals of reference designate corresponding parts in all the views of the drawings.

My novel safety attachment is designed to be secured to any style of clothes wringer constructed in the well known manner but for the purposes of illustration, I have shown a wringer comprising the frame 1, in which are supported the usual wringer rolls 6 and 7, of rubber or other suitable composition, and the said rollers are closed as operated by the gears 8 and 9, from a source of energy in the ordinary manner. In order to regulate the pressure on the rollers, I illustrate the springs 4, and the thumb screw 5, and properly positioned on the frame 1 are the clothes guide boards 3.

Supported to one of the guide boards

3 by means of finger clips 20, is a table or shelf 19, the same being preferably inclined as illustrated, with the edge nearest the machine positioned in close proximity to the bite of the rolls 6 and 7. The guide brackets 14 and 18 are secured in any approved manner to the shelf 19 and operatively supported by the said shelf 19 and brackets 14 and 18 is my novel clothes feeding device 15 that extends the full width of the machine and is comparatively narrow as illustrated. The fingers 16 are attached to the inner edge of the feeding device 15 and they rest and slide upon the table or shelf 19 incident to the operation hereinafter set forth.

The inner ends of the fingers or tips 16 are designed to reach into close proximity of the rolls 6 or 7 and the outer edge of the feeding device 15 is intended to rest and slide upon the guide brackets 14 and 18 above referred to.

In order to impart a reciprocating motion to the feeding device from the wringer roll gear 8 of roll 6 I provide a crank plate 10 that is secured to the outer side of the gear 8 and the link 12; said link being secured in an operative manner to the plate 10, by means of the pin 11, and the link is further secured to the feeding device by the pin 14'. At this point I deem it proper to set forth that in the ordinary construction of wringer machines there are but one set of gears 8 and 9 and therefore in order to assure the even operation of the feeding device 15 I provide a rod 22' suitably supported by brackets 22 to the wringer frame 1. This rod extends completely across the machine to the opposite side thereof and secured to said opposite end of the rod are arms 23 and 23'; the arm 23 being loosely connected by means of a link 24 to the pin 11 on the crank plate 10 and by reason of such connection, these members are permitted to operate synchronously with the link 12 upon rotation of the gears 8 and 9 and crank plate 10.

Because of the fact that there are no gears or crank plate on the opposite side of the wringer, the arm 23' complementary to the arm 23 is attached direct with the link 12 on the opposite side of the wringer, thus eliminating a link similar to the one 24. The links 12 are connected in a removable manner to the feeding mechanism 15, as for example the said links may be slotted

at 12' to receive the pin 14' which are inserted in the ends of the feeding device as shown in Figure 1 and in order to secure the device in position I employ by preference a T-shaped latch 13 suitable for its purpose.

It will be manifest from the foregoing that incident to the rotation of the rolls 6 and 7 the feeding device 15 will be caused to oscillate forwardly and backwardly by reason of the connecting links and hence by laying the clothes to be wrung upon the feeding device 15 in such a manner that the fingers 16 will serve to push same into the bite of the rolls, it is easily seen that the liability or danger of getting one's fingers caught between the rolls and subsequent danger of serious injury is practically eliminated.

In order to hold the feeding device 15 and more particularly the fingers 16 in an approximate contact with the shelf or table 19 I provide the spring clip rod 17 that is attached to the edge of the feeding device by staples or otherwise and the ends of said rod 17 rest beneath the links 12. In certain construction of wringing machines there is provision for wringing clothes either from the right or left side and although I have shown my device as secured to the left of the rolls I would distinctly have it understood, that when it is desired to enter the clothes on the right and leave at the left it is simply necessary to transfer my device by releasing the pins 14' of the feeding device 15 by disengaging the latch 13 and then remove said device and pins from the slotted portions 12' in the links 12. The shelf 15 is then removed by disengaging the finger clips 20, from the guide board 3 on the left hand side of the rolls and place the shelf 15 in a similar position on the guide board 3 at the right side of the rolls. The clips 20 are then engaged by the right hand guide board 3 and the links 12 are swung over to the right of the machine (opposite to the position illustrated) and the feeding device 15 is properly positioned on the wringer. It is also necessary to provide the link 24 intermediate the arm 23 and link 12 because of the fact that the reversing operation would be impracticable without said link, and thus it will be seen that the link 24 is required on one side as its purpose is to operate the rod 22' and its connecting elements when the feeding device has been positioned on the right side of the wringer.

Having described my invention, what I claim and desire to secure by Letters Patent is:—

1. In an automatic feeding mechanism, the combination of a wringer having a frame, rolls arranged in the frame, pressure regulating means mounted above the rolls gears

formed on the ends of the rolls, a shelf inclined from the rolls and entering the bite thereof and secured to the frame, a feeding table mounted above the shelf and having fingers adapted to be forced on the shelf, pins for holding the fingers above the shelf, a latch for preventing casual displacement of the pins from the table, links extending from the table, a cam having a pin connected with one end of one link; said cam being secured to one of the gears of one roller, a link secured to the cam, a rod secured by a short link to the last named link and extending across the length of the rollers, a short link secured to the opposite end of the rod and also secured to a link that extends from one of the pins, and brackets for holding the rod in proper position on the frame whereby rotary motion of the rolls will impart oscillating motion to the table.

2. In automatic clothes feeding mechanism, the combination of wringer rolls, gears secured to one side of the rolls, links extending on the sides of the rolls; one of said links having one end secured to an eccentric plate that is secured to one of the gears, slots formed in the outer ends of the links, a table removably arranged on the links and having pins that are removably locked in the slots of the links to prevent casual displacement of the table; the inner end of the table having inwardly tapered fingers inclined toward the rollers, a table arranged below the first named table and entering the bite of the rollers and a rod adapted to assist even oscillation of the first named table on rotation of the rollers.

3. In an automatic feeding mechanism, the combination of a wringer rolls, pressure regulating means above the rolls, gears formed on one end of each roll, a shelf extending at one end into the bite of the rolls, a feeding table arranged on the shelf and comprising fingers adapted to be moved over the shelf, means for locking the feeding table on the shelf, links extending from the table, a cam having a pin secured thereto and also being secured to one of the roller gears, a rod secured by a short link to the last-named link and extending across the length of the rollers, a short link secured to the opposite end of the rod and also to a link that extends from one of the pins, and brackets for holding the rod in position on the frame.

In testimony whereof I have hereunto set my hand in presence of two subscribing witnesses.

JOSEPH DECELLES.
